UNITED STATES PATENT OFFICE.

FREDERICK DOUGLASS COPPOCK, OF GREENVILLE, OHIO.

DESIGN FOR A TEXTILE FABRIC.

Application filed May 11, 1927. Serial No. 21,930. Term of patent 3½ years.

To all whom it may concern:

Be it known that I, FREDERICK DOUGLASS COPPOCK, a citizen of the United States, residing at Greenville, in the county of Darke and State of Ohio, have invented a new, original, and ornamental Design for a Textile Fabric, of which the following is a specification, reference being had to the accompanying drawing, forming a part hereof.

The figure is a plan view of the ornamental

design for a textile fabric and with the dominant feature residing in irregular shaped projections outlining shaded panels or areas forming bands of a color contrasting in color to the back-ground of the fabric.

What I claim is:

The ornamental design for a textile fabric, as shown and described.

FREDERICK DOUGLASS COPPOCK.
